United States Patent Office.

JOHN J. SWITZER, OF ROXBURY, ASSIGNOR TO HIMSELF AND EDWIN H. FITTZ, OF NORTHBOROUGH, MASSACHUSETTS.

Letters Patent No. 80,885, dated August 11, 1868.

IMPROVEMENT IN STOP-MOTION FOR LOOMS.

The Schedule referred to in these Letters Patent and making part of the same.

TO ALL WHOM IT MAY CONCERN:

Be it known that I, JOHN J. SWITZER, of Roxbury, in the county of Norfolk, and State of Massachusetts, have invented a new and improved Loom; and I do hereby declare that the following is a full, clear, and exact description thereof, which will enable others skilled in the art to make and use the same, reference being had to the accompanying drawings, forming part of this specification.

Figure 1, Sheet I, represents a vertical transverse section of my improved loom.

Figure 2, Sheet I, is a detail transverse section of the apparatus for detaining the flat-board.

Figure 3, Sheet II, is an end elevation of my improved loom.

Figure 4, Sheet II, is a detail vertical section of the same, taken on the plane of the line $x x$, fig. 3.

Figure 5, Sheet III, is a plan or top view, partly in section, of my improved loom.

Similar letters of reference indicate corresponding parts.

This invention relates to a new attachment to looms, which has for its object to instantly cause the stopping of the machinery so soon as one of the warp-threads breaks, as threads frequently break during the weaving process, and as, by their breaking, much annoyance is caused to the weaver and injury to the fabric, this invention will be of great benefit to all manufacturers of woollen and cotton goods; more so, as it is easily applicable to all looms of suitable construction.

When a thread breaks on fine goods, it is not always discovered at once, and if the weaving is continued, the whole fabric is spoiled.

My invention consists in a thread-detector, so arranged and applied to an ordinary or suitable loom, that at the moment a thread breaks, the loom will instantly stop, and cannot proceed until the severed thread has been repaired by the attendant. The thread-detector is altogether out of the way of the working parts of the loom, and does not in the least interfere with the operation of the same as long as all the threads are in order. The invention consists chiefly in the use of a series of pivoted wings, from which warp-supporting rods or threads are suspended, on the lower ends of which loops or eyes are formed for the warp-threads to pass through. So long as the warp-supporting rods or suspended threads are kept tense by the warp-threads, they hold the wings in such a position that the same do not interfere with the motion of a rising and falling flat-board, but so soon as a warp-thread breaks, it will cause the release of a warp-supporting rod or cord, and the wing from which the same is suspended will swing on its pivot, so as to bring an arm projecting from it in the way of the aforesaid flat-board, arresting the downward motion of the same. The flat-board, when arrested, will cause a shaft, that moves also up and down, to oscillate, and by this oscillating motion of the shaft, a lever will be moved, which, by means of cords, a sliding frame, and stop, and bell-crank lever, as hereinafter particularly described, is connected with the sliding rod which operates the belt-shifting lever. As soon as the said rod is released, by the withdrawal of the stop, it will, by the action of a spring or weight, be moved, so as to shift the belt to a loose pulley, and to thus stop the loom. On the shifting-rod is also a stop, which, as soon as the rod is moved by the spring, comes into the way of the batten, and immediately arrests the motion of the same.

Thus, whenever a thread breaks, the motion of the loom is immediately arrested.

A, in the drawing, represents the frame of a loom of ordinary or suitable construction.

B is the main driving-shaft arranged in the same, which, by means of suitable connecting-rods $a a$, imparts oscillating motion to the batten-frame C, which is suspended in the ordinary or in suitable manner.

D D are the harness-frames, arranged as usual, and provided with heddles $b b$. The harness-frames are moved by means of cams $c c$, on a shaft, E, which receives rotary motion, by gearing or other connection, from the shaft B. All these parts A B C D E, and $a b c$, as well as their various connections and appendages, are of ordinary or suitable construction, and do not form part of this invention.

On the shaft B are mounted two cams $d d$, upon the edge of which rest the lower ends of vertically-sliding bars F, the rotary motion of the cams imparting the reciprocating motion to the bars. The lower ends of the

bars carry rollers e , which serve to lessen the friction produced on the edges of the cams. The upper ends of the bars F are connected by means of a horizontal shaft or rod, G . Upon shoulders f , formed on bars F F' , rests and is supported a flat-board, H , which rises and falls with the bars F , said flat-board being below the shaft G , as is shown in fig. 1.

The flat-board, instead of being made of one piece, may be made of two or more independent pieces, as may be desired.

The shaft B receives its motion from a belt, running on a pulley, g , a forked lever, I , serving to shift the belt upon a loose pulley, h , shown in fig. 5.

The lever I is pivoted to the frame of the loom, and its rear end is connected with a sliding bar, J , which is moved longitudinally in its bearings, so as to swing the lever I on its pivot; and thus, by sliding the bar J , the belt can be shifted to the loose or fixed pulley, as may be desired, to stop or start the machine.

K K' are a series of sheet-metal or other plates, pivoted to horizontal shafts L , having their bearings in the frame of the loom, under and parallel with the flat-board H .

The wings K have each three arms, i , j , and l .

From the arm i is suspended a cord or string, m , which has at its lower end an eye or loop, through which another cord, n , is drawn, both ends of which have loops o , as in fig. 1. Each warp-thread passes through a loop, o , and as the warp-threads are held tense, they will also hold the cords m n tense, and thereby the arms i of the wings down.

The cords n may be dispensed with, and the warp-threads be drawn directly through the loop at the lower ends of the threads m , but in that case a thread, m , would be required for each warp-thread, while, with the threads n , but one thread m for a pair of warp-threads is required. Instead of the threads m , rods or wires may be employed.

The arms j of the wings K extend upwards, as in fig. 1, and are, when the flat-board moves down, swung down by the said flat-board, as shown by red lines in fig. 1, as hereinafter more fully set forth. The arms l of the wings K , act as weights to keep the strings m tense, and the arms i and j up, so that when the flat-board moves up, the wings will at once resume their original position.

Should one of the warp-threads break, the weight l of the wing with which such warp-thread was connected will at once cause the arm j of the wing to assume a vertical position above the shaft L , as shown on the left-hand side of fig. 2.

When, then, the flat-board comes down, it will, by the thus elevated arm j , be prevented from descending to the shoulders f , while the downward motion of the bars F , and of the shaft G , will not be arrested. When the flat-board is thus held up by a wing, K , while the shaft G moves downwards, projecting lugs, p , on the shaft, will strike against lugs r , projecting from the flat-board, and the shaft will thereby be turned, as indicated in fig. 2. The projection p was, before the shaft G came in contact with the flat-board, held in a horizontal position by a suitable spring or weight, s , as in fig. 1, and is then turned up, as in fig. 2, whereby the turning of the shaft G is produced.

From the above it will be fully understood that whenever a warp-thread breaks, the shaft G will at once be turned by the arrested flat-board.

The wings K may be arranged differently, and I do not confine myself to the particular shape or form, but simply to their being so arranged, and provided either with weights or springs, that they will, as soon as their connections with the warp-threads are interrupted by the breaking of a warp-thread, at once swing on their pivots, and arrest the flat-board, as set forth.

M is a lever or bar, hinged to one side of the frame A , and connected at its free end by means of a cord, t , with a pin, v , as shown in fig. 3. The pin v has as its lower end a block, w , as in fig. 4.

N is an elbow-crank, pivoted to the frame A , and connected at one end with the sliding bar J , while its other end is, by means of a string, y , connected with the frame O , sliding in a stationary case, P , in front of the pin v , as indicated in fig. 4.

In the frame O is pivoted, or otherwise arranged, a hook, z , as shown in fig. 4, which hook has a cam-shaped projection, a' , at its inner edge, opposite the pin v .

b' is a cam, mounted on the shaft B , and oscillating a lever, R , pivoted to the frame A , as in fig. 3. The lever R carries a sliding block, S , up and down in front of the hook z .

When the frame O is elevated, as in fig. 4, and the hook drawn in, the slide J will be in the position shown in fig. 5, holding the lever I on the fixed pulley, a spring, c' , tending to retain the slide in this position.

As soon as the shaft G is turned, it will, with a crank or cam, d' , at its end, swing the lever M on its pivot, so that the same will draw the cord t , which will raise the pin v . As the pin is raised, its block, w , will strike against the projection a' of the hook z , and will push the hook out into the way of the slide S . As soon as the slide S is now moved down by the action of the cam b' and lever R , it will carry the frame O down with it, and the frame O will draw the string y , and will turn the bell-crank N on its pivot, so as to draw the slide J towards the crank. By such motion of the slide J , the lever I will be turned, and will shift the belt upon the loose pulley.

The connection between the shaft G and the slide J may be arranged in a different manner from that described, although the latter is quite simple, and operates satisfactorily.

T represents a swinging plate, held by a spring, e' . The rod J , by means of which the shifting-lever I is operated, is provided with a projecting pin, f' , which rests against the plate T . When the rod J is moved, to shift the belt from pulley g to h , the pin f' is withdrawn from the plate T , which, by the contraction of the spring e' , is caused to assume the position shown in red lines. The plate T is then in the way of a pin, g' , projecting from the under side of the batten C , and will thus also at once arrest the motion of the batten. When the broken thread has been adjusted, the pin v must or may be pushed down, the hook z pushed in, and the slide J readjusted, when the parts will all be again in working position.

To prevent the threads *m* from getting entangled, they had better be guided through a horizontal reed, *u*, as is clearly shown in fig. 1.

The lever *R* is, by means of the cam *b'* on the shaft *B*, or on any other shaft, moved down, and is raised again by means of a spring, *h'*, or its equivalent.

Instead of all the springs herein mentioned, weights may be used, and in place of all the weights mentioned, springs may be employed, as may be desired.

The driving-shaft receives its motion from suitable mechanism.

I claim as new, and desire to secure by Letters Patent—

1. The wings *K K*, constructed substantially as described, and provided with the warp-supporting cords or rods, in combination with the rising-and-falling board, as and for the purpose set forth.
2. The flat-board *H*, the vertically-movable frame *F*, and the wings *K*, as and for the purpose set forth.
3. The vertically-movable frame *F*, carrying the flat-board *H* and the shaft *G*, substantially as herein shown and described.
4. The lugs *r*, projecting from the flat-board, in combination with the lugs *p*, projecting from the rock-shaft *G*, all made and operating substantially as and for the purpose herein shown and described.
5. The slide *J*, connected with the shifting-lever *I*, spring *c'*, and elbow-crank *N*, substantially as herein shown and described.
6. The devices herein shown and described, for transferring motion from the rock-shaft *G* to the elbow-crank *N*, said devices consisting of the lever *M*, cord *t*, pin *v*, hook *z*, frame *O*, and string *y*, all made and operating substantially as herein shown and described, in combination with the vibrating-lever *R* and block *S*, made as set forth.
7. A thread-detector, consisting of the wings *K K*, threads *m*, frame *F*, shaft *G*, flat-board *H*, lugs *p r*, cam *d'*, lever *M*, string *t*, pin *v*, hook *z*, frame *O*, cord *y*, elbow *N*, slide *J*, and shifting-lever *I*, all made and operating substantially as herein shown and described.
8. The swinging arm *M*, cord *t*, pin *v*, and block *w*, in combination with the hook *z*, having the inner projection *a'*, and hinged in the frame *O*, and combined with the slide *S*, all made as set forth.

The above specification of my invention signed by me, this 12th day of March, 1868.

JOHN J. SWITZER.
